UNITED STATES PATENT OFFICE.

CHRISTOPHER M. DALY, OF BRIDGEPORT, CONNECTICUT.

FUSE.

Application filed July 20, 1921. Serial No. 486,068.

To all whom it may concern:

Be it known that I, CHRISTOPHER M. DALY, a citizen of the United States, residing at Bridgeport, in the county of Fairfield and State of Connecticut, have invented certain new and useful Improvements in Fuses, of which the following is a specification.

This invention relates to fuses especially adapted for use in light sockets.

An important object of this invention is to provide a fuse which may be detachably arranged in a light socket between the central contact of the socket and the center contact of the light bulb so that should the light break and become short circuited all the lights on that circuit will not go out.

A fuse constructed in accordance with this invention will eliminate the formation of objectionable flashes or arcs which radiate from a light socket when the bulb attached to the socket is short circuited for any reason.

A further object of the invention is to provide a fuse of the class described which may be readily and conveniently attached to a bulb and which is extremely cheap to manufacture.

Other objects and advantages of the invention will be apparent during the course of the following description.

In the accompanying drawing forming a part of this application and in which like numerals are employed to designate like parts throughout the same,

Figure 1 is a side elevation of a light socket equipped with the improved fuse, the socket being partly shown in section.

Figure 2 is a vertical sectional view through the fuse.

Figure 3 is a plan view of the fuse opened to illustrate the fusible member and the contacts connected to the ends of the same.

In the drawing wherein for the purpose of illustration is shown a preferred embodiment of the invention the numeral 5 designates a socket of the usual construction, which socket has electrical connection with an electric line designated by the numeral 6. The wire 6 may be one branch of a circuit having a number of other sockets to which lights are connected. The bulb 7 which is threaded into the socket is provided with the usual center contact which ordinarily engages the center contact 8 of the socket whereby the current is transmit-

ted from the socket to the filaments of the lamp.

The invention forming the subject matter of this application resides in a fuse generally designated by the numeral 10 and which as illustrated in Figure 1 is adapted to be detachably arranged between the inner wall of the socket and the forward end of the light bulb. The body of the fuse consists of a pair of preferably integral disks 11 of mica or other suitable material and which are joined as indicated at 12. The center of each disk is provided with a metallic contact 13 having its outer side formed with an enlarged head adapted to be engaged either with the center contact 8 of the socket or with the center contact of the attaching portion of the bulb. Since there are two contacts 13 one contact is engaged with the contact 8 and the other is engaged with the center contact of the light bulb, whereby the current supplied to the lamp is passed through a fuse wire 14 having its ends secured to the contacts 13.

As illustrated particularly in Figure 3 the intermediate portion of the fuse wire 14 is coiled as indicated at 15 and is received within an arcuate compartment 16 at the outer edge portions of the disks 11. The arcuate compartment 16 is formed by pressing the disks 11 outwardly at their adjacent portions. In assembling the fuse a suitable powder may be arranged in the arcuate compartment so as to prevent the radiation of an arc or flash from the fuse when the same blows. An insulating disk 18 is provided with an attaching tongue 19 imbedded in one edge of one of the disks 11, the said insulating disk 18 being adapted to be arranged between the disks 11 when the fuse is assembled. It will be seen that the insulating disk 18 prevents engagement of the contacts 13 with each other.

In use the fuse may be detachably arranged within the socket and when the bulb becomes short circuited for any reason the fuse will blow thereby preventing the radiation of arcs or flashes. The fuse is extremely cheap to manufacture and will prevent an entire circuit from being placed out of commission when one of the lights is short circuited.

I claim:

1. A fuse comprising a pair of integral disks, contacts carried by the disks and having heads arranged on the outer sides of

the same, and a fuse wire connected to said contacts.

2. A fuse comprising a pair of integral disks, contacts carried by the disks and having heads arranged on the outer sides of the same, a fuse wire connected to said contacts, and having its intermediate portion coiled, and an insulating disk of insulating material arranged between said first named disks.

10 3. A fuse comprising a pair of integral disks, contacts carried by the disks and having heads arranged on the outer sides of the same, a fuse wire connected to said contacts, and having its intermediate portion coiled,

and an insulating disk of insulating material 15 arranged between said first named disks, said disks being provided with struck out portions defining an arcuate compartment receiving said coiled portion, said insulating disk being provided with an attaching 20 tongue imbedded in one of said first named disks.

In testimony whereof, I have affixed my signature in the presence of two witnesses.

CHRISTOPHER M. DALY.
